UNITED STATES PATENT OFFICE.

HENRY A. OWEN, OF WHITINSVILLE, MASSACHUSETTS.

WARP STOP-MOTION FOR LOOMS.

SPECIFICATION forming part of Letters Patent No. 703,666, dated July 1, 1902.

Application filed March 11, 1901. Serial No. 50,666. (No model.)

To all whom it may concern:

Be it known that I, HENRY A. OWEN, a citizen of the United States, residing at Whitinsville, in the county of Worcester and State of Massachusetts, have invented a new and useful Improvement in Warp Stop-Motions for Looms, of which the following is a specification.

This invention has reference to the class of warp stop-motions in which the detector-plates are supported on the warp and connect with a mechanism when a warp-thread breaks, whereby the loom is stopped.

The invention consists in the peculiar and novel construction and the combination of the detector-plates with the mechanism whereby the detector-plates when released connect a rocking mechanism with the loom stop mechanism, as will be more fully set forth herein-after.

Figure 1 is an end view of a portion of a loom, showing the parts of a loom with which the warp stop-motion coöperates. Fig. 2 is a side view, on an enlarged scale, showing the normal position of the detector-plates, the rocking mechanism and the supporting-tube being shown in section. Fig. 3 is a side view, partly in section, showing the detector-plate in the operative position. Fig. 4 is a top view, partly in section, of one end of the rocking mechanism, showing the actuating-lever secured to the rocking shaft and the actuated lever secured to the tube. Fig. 5 is a sectional view of the rocking tube and shaft, showing the detector-plate supported above the warp-thread, a modified form used when the rocking mechanism is placed above the warp.

In the drawings, A indicates the end frame of the loom, B the warp-beam, C the breast-beam, D the lay, E the warp, and F the cam-shaft, of a power-loom.

In Fig. 1 the above-referred-to parts are shown in their relative positions as commonly used.

In applying my improved warp stop-motion I secure the bracket *a* to a fixed part of each of the end frames A. In Fig. 1 the bracket *a* is shown secured to the bracket *a'*, which is secured to the end frame. The tube *b* has in its upper side the longitudinal slot *b'* and is supported at its ends in bearings formed in the brackets *a a*, so that it may be rocked in

these bearings. To one end of the tube *b* the lever *b²* is secured, as shown in Fig. 4. The connecting-rod *b³* connects the free end of the lever *b²* with the rod *b⁴*, which normally rests on the pin *b⁵*, projecting from the end frame A. The rod *b⁴* is provided with the shoulder *b⁶*, which when the rod is raised, as is indicated in broken lines in Fig. 1, lies in the path 60 of the bracket *d* on the lay. On the front end of the rod rests the stud *b⁷*. It is preferably provided with a forked end and the shoulder *b⁸*, which engages with the knock-off lever *c*.

Within the tube *b* is supported the rock-shaft *f*. The part of this rock-shaft *f* between the cylindrical ends is of crescent-shaped cross-section, the convex portion of which bears on and may rock on the inner 70 surface of the tube *b*, so as to have the upper edge pass under the slot *b'* in the normal operation of the loom. To the projecting end of the rock-shaft *f* the lever *f'* is secured, as shown in Fig. 4. The connecting-rod *f²* connects the lever *f'* to the crank *f³* on the cam-shaft F.

A series of detector-plates *e* are supported on the warp-threads. Each detector-plate has an eye or opening *e'*, through which a 80 warp-thread is passed, and an elongated opening *e²*, through which the tube *b* extends. The upper part of the opening *e²* preferably contracts in segmental curves, abutting against the stop *e³*, which extends downward 85 into the opening *e²*. The detector-plates *e* are suspended by warp-threads. When a warp-thread breaks, the detector-plate will drop by its own weight, and the opening *e²* is of such shape and dimensions that in dropping the detector-plate *e* will be guided so that the stop *e³* will enter the slot *b'* in the tube *b*, and when the crescent portion of the tube rocks to clear the slot the stop *e³* will pass down into the tube and the path of the 90 crescent portion of the shaft. The detector-plates *e*, supported on the warp-threads, are held against the forward movement of the warp, preferably, by the tube *g*, which is supported on the brackets *a a* on the opposite end 100 frames.

When it is desired to place the warp stop-motion above the warp, the brackets *a a* are made longer, so as to support the tube *b* above

the warp, and the detector-plates *e*, having the warp-eye *e'* below the opening *e²*, (shown in Fig. 5,) are supported by the warp, as is shown in that figure.

5 When the stop-motion is connected with the loom, the operative connections are outside the end frames of the loom in plain sight and accessible for adjustment or repairs. In the normal condition the crank *f³* imparts, 10 through the lever *f'*, a rocking motion to the shaft *f*. The upper edge of the crescent section of the shaft passes under the slot *b'* forward and backward. When now a warp-thread breaks, the detector-plate *e*, engaging 15 with and supported on the warp-thread, drops and the stop *e³* enters the slot in the tube *b* and rides on the crescent section of the shaft until the upper edge clears the slot, as shown in Figs. 2 and 5, when the stop descends and 20 interlocks the shaft *f* with the tube *b*. At this point the crank *f³* and all the operative parts are in the position shown in solid lines in Fig. 1. As the crank *f³* turns into the position shown in broken lines the tube *b* turns, 25 with the shaft *f*, into the position shown in Fig. 3, the lever *b²* lifts the rod *b⁴* into the position shown in broken lines, the lay strikes near the end of its reciprocation against the shoulder *b⁶*, and the shoulder *b⁸* operates the 30 knock-off lever to stop the loom.

Having thus described my invention, I claim as new and desire to secure by Letters Patent—

1. In a warp stop-motion having detector- 35 plates provided with stops and supported on the warp-threads, a tube having a slot, a rocking member in the tube, means for operating the rocking member, and means connected with the tube for stopping the loom upon the 40 breaking of a warp-thread and the entering of the stop on a detector-plate into the slotted tube, as described.

2. In a warp stop-motion, the combination with a series of detector-plates provided with 45 stops and individually supported on warp-threads, of a longitudinally-slotted tube, journal-bearings supporting the ends of the

tube, a rocking member in the tube, means for operating the rocking member across the slot in the tube, a stop-rod provided with a knock-off shoulder, and mechanism connected with the knock-off rod and the tube, whereby upon the breaking of a warp-thread and the dropping of the detector-plate the rocking member and the tube are caused to move 55 together and the loom stopped, as described.

3. A detector-plate for a warp stop-motion for looms having an oblong opening with parallel sides, one end of which opening is curved inward to a central stop projecting into the 60 opening, and an eye or opening for the passage of a warp-thread, as described.

4. In a warp stop-motion for looms, the combination with the tube *b* having the slot *b'*, the lever *b²*, the connecting-rod *b³*, the stop-rod *b⁴* provided with a knock-off shoulder and connected with the knock-off lever, and the shaft *f* having the crescent portion, of the detector-plate *e* having the projection *e²* extending into the opening of the detector-plate and 70 adapted to enter the slot *b'*, whereby the crescent-shaped section may be locked to the tube upon the breaking of the warp-thread, as and for the purpose described.

5. In a warp stop-motion for looms, the 75 combination of the following instrumentalities: a longitudinally-slotted tube, a vibrating member in the tube, mechanism for operating the vibrating member, a series of detector-plates supported on the warp-threads, an 80 oblong opening in each detector-plate, a stop projecting into the opening at one end and adapted to enter the slot in the tube upon the breaking of the warp-thread, and mechanism connecting the tube with the stop-lever of the 85 loom, as described.

In testimony whereof I have signed my name to this specification in the presence of two subscribing witnesses.

HENRY A. OWEN.
